UNITED STATES PATENT OFFICE.

WINFIELD WILLIAMS, OF SAN JOSE, CALIFORNIA, ASSIGNOR, BY DIRECT AND MESNE ASSIGNMENTS, TO J. F. PATTERSON AND HORTENSE BEAN, A COPARTNERSHIP OPERATING AS PATTERSON-WILLIAMS MFG. CO., OF SAN JOSE, CALIFORNIA.

AMUSEMENT DEVICE.

1,426,624.

Specification of Letters Patent. Patented Aug. 22, 1922.

Application filed June 30, 1920. Serial No. 393,010.

To all whom it may concern:

Be it known that I, WINFIELD WILLIAMS, a citizen of the United States, and resident of San Jose, in the county of Santa Clara 5 and State of California, have invented certain new and useful Improvements in Amusement Devices, of which the following is a specification.

My invention relates to an amusement device involving a combination of revolving and oscillating members.

It is the object of my invention to provide an amusement device of the character indicated in which the essential features are 15 capable of varied application; in which one member is freely revoluble through the action of the hands or feet of the operator as the case may be; in which the same member is caused to revolve with an undulating movement by the operator thereof; in which resilient means are utilized for normally holding the revoluble member in a horizontal position; in which a novel form of bearing is provided whereby the desired freedom of 20 action is secured and the effective life of the device prolonged. Finally it is the object of my invention to provide a device of the character indicated that will be simple in form, economical to manufacture, durable, and highly efficient in its practical 25 application.

In the drawing:

Figure 1 is a plan view of one embodiment of my invention, part being broken 35 away.

Figure 2 is a section on line 2—2 of Figure 1.

Figure 3 is a side elevation of another embodiment of my invention.

Figure 4 is a side elevation of still another embodiment of my invention.

Referring more particularly to the drawing, 1 indicates a base member upon which is bolted a bearing member 2 having an inverted truncated cone shaped socket formed in the upper surface thereof as shown at 3 and having a vertically and concentrically positioned post 4 cast integrally therewith as shown, and having annular grooves 5 formed therein to receive ball bearings 6 as shown.

At 7 is shown an inverted truncated cone shaped member mounted to revolve on post 4 and positioned within and spaced a dis-

tance from socket 3 and supported on balls 55 6. Member 7 carries a flange 8 extending a distance beyond the outer and upper edge of bearing member 2 and spaced a distance above the same. Member 7 also has an upper portion 9 rising a distance above 60 flange 8 as at 10 and provided with a convexly rounded surface 11 concentrically arranged with respect to post 4.

At 12 I show a circular platform having a substantially larger diameter than flange 65 8 and preferably built up of boards 13 secured together by cleats 14 and having a reinforcing and bearing plate 15 arranged concentrically thereto on its under surface. Platform 12 and plate 15 are provided with 70 an orifice 16 at the center thereof of somewhat larger diameter than post 4 over which these members are placed so as to rest on the rounded surface 11 of member 9. A collar 17 is secured to post 4 a distance 75 above platform 12 to prevent the wilful removal of said platform from said post.

At 18—18—18—18 are shown bolts secured at their upper ends to platform 12 and plate 15 by nuts 19 and extending 80 downwardly through orifices 20 in flange 8 and terminating a distance below said flange and fitted with washers 21. Each bolt 18 is fitted with a spring 22, the same being inserted between washer 21 and a second 85 washer 23 engaging the under side of flange 8. In the embodiment shown in Figures 1 and 2 the upper end of post 4 is fitted with a cap member 24 threaded at 25 to engage the threaded ends of laterally projecting pipe members 26, the latter being four in number in the present case. In this embodiment I also show a plurality of equally spaced and radially arranged cleats 27 secured to the upper surface of platform 12. 90

Since the platform 12 is mounted to tilt on member 9 as indicated in dotted lines at 28, the orifice 16 must be made sufficiently large to permit the free tilting of said platform without the edge of said orifice engaging said post. Also since bolts 18—18—18—18 are fixedly secured to platform 12 and tilt therewith the orifices 20 through which they pass must also be made sufficiently large to permit the free tilting of 105 said bolts.

The platform 12 may be caused to revolve by children grasping the rods 26 and apply-

ing force to cleats 27 with their feet. Since the rods or arms 26 are stationary the platform 12 is caused to revolve after the manner of a treadmill. The platform may also be propelled by the children sitting on the edge thereof and applying their feet to the ground. It is clear of course that when platform 12 revolves the several members 15—9—19—8 and 7 revolve with it about stationary post 4 and on bearings 6. Since no grooves are formed for balls 6 in cone shaped member 7 any wear incident to continued use of the device is automatically compensated for by the settling of member 7 further into socket 3. The rotating movement of platform 12 is imparted to member 7 through the medium of bolts 18 and frictional contact with the upper part of surface 11.

If a weight is applied to any portion of platform 12 sufficient to over balance the same, as for instance the weight of a child at 29, then the bolt or bolts 18 on that side take a tilted position as shown in dotted lines at 30, and bolts 18 on the opposite side to the said weight take a position as indicated at 31, placing their springs 22 under compression.

The result of this construction is that the platform 12 will revolve freely at all times and by proper manipulation as in play the same may be caused to assume an infinite variety of angular positions, but will always automatically assume a substantially horizontal position when at rest.

In Figure 3 I show an embodiment of my invention in which post 4 is omitted. In this embodiment the bearing member is supported a distance from the ground by legs 32 and a cap member 33 is held in position on surface 11 of member 9 by bolts 18, the cap member 33 having a number of radially arranged bars 34 fixedly secured thereto. In this case the cap member 33 and bars 34 operate on surface 11 and with rotating member 7—9 in exactly the same manner as platform 12 described in connection with Figures 1—2.

The operation of the structure shown in Figure 4 is identical with that described in connection with Figure 3 except that each bar 34 carries a swing 35 provided with a bumper 36, the swings being pivotally connected to said bars at 37.

It is understood of course that changes in form, construction and arrangement of the several parts, members and features may be made within the scope of the appended claims.

I claim:

1. A device of the character indicated comprising a support, a member revolubly mounted on said support and presenting a convex upper surface, a member supported on said convex surface, a plurality of ele-

ments rigidly secured to one of said members and passing through the other member, and a resilient connection between each of said elements and said last mentioned member.

2. A device of the character indicated comprising a support, a member revolubly mounted on said support and presenting a convex upper surface and having a plurality of orifices formed therein, a member supported on said convex surface, a plurality of elements rigidly secured to said second mentioned member and passing through the orifices in said first mentioned member and resilient connections between said elements and said first mentioned member.

3. A device of the character indicated comprising a support, a member mounted to revolve thereon about a vertical axis, a second member operatively mounted on said first member to revolve therewith, the engaging surface of said members being unbroken and formed to permit the tilting in any direction of said second mentioned member on said first mentioned member, and resilient means for normally holding said second mentioned member in a predetermined position with relation to said first mentioned member.

4. A device of the character indicated comprising a support, a member revolubly mounted on said support and having a plurality of orifices formed therein adjacent the perimeter thereof, a second member operatively mounted on said first mentioned member, a plurality of depending elements rigidly secured to said second mentioned member and passing through said orifices, resilient connections between said depending elements and said first mentioned member, and means for permitting the tilting in any direction of said second mentioned member on said first mentioned member whereby some of said resilient means are compressed.

5. A device of the character indicated comprising a support, a post axially mounted in fixed relation thereto, a member revolubly mounted in said support and on said post and presenting a supporting surface, a platform mounted on said supporting surface to revolve with said member about said post, means for permitting the tilting in any direction of said platform on said member, and laterally extending arms mounted on said post a distance above said platform whereby a propelling means may be held in a given position while its energy is applied to the upper surface of said platform.

6. A device of the character indicated comprising a support, a post axially mounted in fixed relation thereto, a member revolubly mounted in said support and on said post, a platform mounted on said member to revolve therewith about said post and having an enlarged central orifice through which said post passes, means for permitting the tilting

of said platform in any direction on said member, resilient connections between said platform and said member for normally holding said platform in a given position, 5 and laterally extending hand bars mounted on said post a distance above said platform.

7. A device of the character indicated comprising a support, having an inverted cone shaped socket formed therein, ball bearings 10 operatively arranged in said socket, a post axially arranged in a fixed position in said socket, a cone shaped member operatively mounted to revolve on said ball bearings and about said post, a platform operatively 15 mounted to tilt in any direction on said member, depending elements fixedly secured to said platform and extending below the upper portion of said member, resilient ele-

ments inserted between the ends of said elements and the upper portion of said member, and a plurality of laterally extending arms mounted on said post a distance above 20 said platform.

8. A device of the character indicated comprising a support, a member revolvably 25 mounted on said support and presenting a supporting surface, a platform mounted on said supporting surface, to revolve with said member, means for permitting the tilting in any direction of said platform on said member, depending elements secured to said platform resilient elements mounted on said member, depending elements, and means carried by 30 said first mentioned revolvable member for engaging said resilient elements.

WINFIELD WILLIAMS.
